Primary Examiner — Eric Goodman*Assistant Examiner* — Daniel J Domino*(74) Attorney, Agent, or Firm* — James D. Wyninegar, Jr.(57) **CLAIM**

The ornamental design for a display screen of a medical pump with a graphical user interface, as shown and described.

DESCRIPTION

The FIGURE is a front view of display screen of a medical pump with a graphical user interface, showing the new design.

The broken lines in the drawings illustrate portions of an environmental medical pump and portions of the graphical user interface thereof that forms no part of the claimed design.
